UNITED STATES PATENT OFFICE.

FRANK DI IONNO, OF MILLBURN, NEW JERSEY.

DESIGN FOR A PENHOLDER OR SIMILAR ARTICLE.

Application filed February 19, 1927. Serial No. 20,820. Term of patent 14 years.

To all whom it may concern:

Be it known that I, FRANK DI IONNO, a subject of the King of Italy, and a resident of Millburn, in the county of Union and State of New Jersey, have invented a new, original, and ornamental Design for a Penholder or Similar Article, of which the following is a specification, reference being had to the accompanying drawing, forming part thereof.

I claim:

The ornamental design for a penholder or similar article, as shown.

FRANK DI IONNO.
